(57) **CLAIM**

The ornamental design for an upper bar of a planter, as shown and described.

DESCRIPTION

FIG. 1 is a front, right, and top perspective view of an embodiment of an upper bar of a planter;

FIG. 2 is a back, left, and top perspective view of the embodiment of figure

FIG. 3 is a front view of the embodiment of FIG. 1;

FIG. 4 is a back view of the embodiment of FIG. 1;

FIG. 5 is a right side view of the embodiment of FIG. 1 (where the left side view is a mirror image of the right side view);

FIG. 6 is a top view of the embodiment of FIG. 1;

FIG. 7 is a back, left, and bottom perspective view of the embodiment of FIG. 1;

FIG. 8 is a front, right, and bottom perspective view of the embodiment of FIG. 1; and,

FIG. 9 is a perspective view of another embodiment of the upper bar of a planter, this embodiment differing from the embodiment of FIGS. 1–8 only in that any portions of the upper bar between the undulating broken lines form no part of the claimed design.

The broken lines in the drawings illustrate portions of the upper bar of a planter that form no part of the claimed design and any portions residing between the undulating broken lines form no part of the claimed design. The oblique lines residing on the upper bar of a planter represent a transparent surface thereof.

1 Claim, 8 Drawing Sheets
